UNITED STATES PATENT OFFICE.

LAURENCE SARTORE, OF PITTSBURGH, PENNSYLVANIA, ASSIGNOR OF ONE-HALF TO
DECIMO FOGLIA, OF PITTSBURGH, PENNSYLVANIA.

MECHANISM FOR PREPARING SKINS FOR STITCHING.

Application filed February 19, 1921. Serial No. 446,503.

To all whom it may concern:

Be it known that I, LAURENCE SARTORE, a citizen of the United States, and resident of Pittsburgh, in the county of Allegheny and 5 State of Pennsylvania, have invented a new and useful Improvement in a Mechanism for Preparing Skins for Stitching, of which the following is a specification.

This invention relates to a stitching mechanism for preparing sausage skins for stitching to form bags or cases for sausages of relatively large size.

It is necessary for sausages of certain sorts that bags or cases of considerable size and 15 strength be provided. In order to make such bags or cases, it is necessary to superimpose two or more layers of the original gut used for making the bags; to split the multiple-ply material thus provided; and to stitch it 20 along its edges to form a sausage bag or case of increased diameter.

The object of the present invention is to provide mechanism for superimposing the layers of gut; for splitting them longitudinally; and for so mounting the layers thus 25 split that they are suitably supported for the subsequent stitching operation.

More specific objects of the invention are to provide means whereby the several layers 30 of gut may be superimposed without pulling or tearing; and by means of which the layers first applied to the gut holding means are held against wrinkling during the application of succeeding layers.

35 In the accompanying drawings Figure 1 is a side elevation of the mechanism; Figure 2 is a front elevation thereof; Figure 3 is a longitudinal section through the mandrel for receiving the gut; Figure 4 is a cross sectional view therethrough on the line 4—4 Fig. 3; Figure 5 is a front elevation of the mandrel supporting brackets of the device; Figure 6 is a fragmentary side elevation of one of such brackets; Figure 7 is an elevation 40 of one of the jointed rods for holding the skins or gut for stitching; Figure 8 is a sectional detail view on an enlarged scale taken on the line 8—8 Figure 3; Figure 9 is a sectional detail view illustrating the op-

eration of splitting the gut on the mandrel; 50 Figure 10 is a fragmentary plan view illustrating in detail a feature of the gut holding rods; and Figure 11 is a longitudinal sectional view of a portion of one of the rods illustrating the same in detail. 55

The mounting means for the device comprise a standard 1 to which a plate 2 is bolted or otherwise suitably secured. On plate 2 are brackets 3 and 4, which are divided for securing in position the mandrel 5, 60 and which are joined by clamping bolts or the like. The mandrel 5, over which the gut is drawn to prepare it for stitching, is a tubular member held immovably in the brackets 3 and 4. Each of the brackets is 65 provided with a centrally disposed orifice 6 in which the operating rod 7 is slidably mounted. This operating rod lies within mandrel 5 and extends both forwardly and rearwardly therebeyond. To the forward 70 extremity of rod 7 the mandrel head 8 is screw threaded or otherwise suitably secured. The head 8 is of such conformation that it presents a surface of generally ovate form for drawing gut thereover and onto the mandrel. Its rearward extremity is formed to lie closely against the forward extremity of the mandrel proper 75 5, and is provided with an inwardly extending rim or flange 9 to fit over and hold sections of gut which have been drawn into position on the mandrel. 80

Mandrel 5 itself is a tubular member provided with a channel 10 for receiving the sections 11 of clamping rods 12. These rods 12 85 are formed in two sections 11 and 13, hinged together at 14; each of the sections 13 being provided with a plurality of pins 15 arranged to enter apertures 16 in the sections 11 when the rods are folded. 90

When the device is arranged to receive sections of gut to be prepared for stitching, sections 11 of the two rods 12 lie in the channel 10 of the mandrel in such position as to leave a space between them. In such 95 position the sections 13 of the rods are held by spring clips 17 of the bracket 18 which is mounted on the plate 2 of the standard. The

forward extremities of the rod sections 11 are locked in position by means of pins 19, on a washer 19^a slidable on the rod 6, and arranged to enter orifices in the extremities 5 of the sections when the washer is forced against the forward extremity of the mandrel by the mandrel head 8.

The rearward extremity of each of the rod sections 11 is provided with a projection 10 20 which may be engaged by a clip 21 carried by a sleeve 22 on the mandrel 5. This sleeve is slidable on the mandrel 5 and is forced forwardly so that clip 21 engages projection 20 by means of a coiled spring 23 15 which surrounds the mandrel and bears against the sleeve 22 and against the more forwardly of the brackets 3. A set screw 24, which passes through sleeve 22 and bears against mandrel 5, holds the sleeve 22 in operative position.

In this position of the parts, a section of 20 25 gut may be drawn over mandrel head 8 and mandrel 5 so that it lies thereon, embracing the sections 11 of clamping rods 12. This section of gut may then be secured in 25 position on the mandrel by operation of the mandrel head 8.

Normally the head 8 is held closely against the forward extremity of the mandrel by 30 35 means of a coiled spring 25, which surrounds the rearward portion of operating rod 6, and which bears against the rearward face of bracket 4 and against a block 26 adjustably secured to the rod. To the block 26 is secured a lever 27 for operation of the rod 7.

With a section of gut on mandrel 5, the lever 27 is operated to force the rod forwardly against the resistance of spring 25; and the section of gut is smoothed manually 40 45 and drawn so far along mandrel 5 that only the forward edge thereof projects beyond the forward extremity of the mandrel. Lever 27 is then released, permitting spring 25 to return the head 8 to position. The flange or rim 9 on the head 8 then engages 50 55 the forward edge of the section of gut on the mandrel to prevent wrinkling of the gut while a succeeding section is being drawn into position. The pins 19 on washer 19^a also re-enter the apertures in the forward extremities of the rod sections 11 to secure these sections in position.

The foregoing operation is repeated until 55 60 two or more layers of gut have been positioned on the mandrel 5. The sections 13 of the rods 12 are then folded over so that the pins 15 thereon pass through all layers of gut and enter the registering apertures 16 in the rod sections 11. The gut is then split longitudinally by any suitable means. As 65 illustrated in Figure 9 of the drawings, a rotating cutter blade 28 may be run along the space between the rods 12 to part the gut throughout its entire length.

In order to remove the gut from the de-

vice, the set screw 24 is loosened and the sleeve 22 forced backwardly against the resistance of coiled spring 23; thus withdrawing clips 21 from the projections on the rearward extremities of the rod section 11. The rods 12, holding the divided material between them, may then be disengaged and lifted from channel 10 in mandrel 5.

In order that the gut may be held securely by the jointed rods 12, the rod sections are preferably provided with special means for holding them in mutual engagement. As shown in detail in Figures 10 and 11 of the drawings, such means comprise one or more split rings 28 which are 75 80 set in a countersunk plate 29 secured to a rod section 11 by set screws 30 or the like. On rod sections 13 are one or more pins 31, of greater length and diameter than the pins 15 thereon. These pins 31 are arranged 85 to match with split rings 28, and have a diameter slightly greater than the internal diameter of such rings. When, therefore, the rod sections are brought into mutual engagement to clamp and hold gut therebetween; these pins enter and spread the split rings 28 so that the pins, and the rod sections 13 which carry them, are securely held to the rod sections 11. The pins 31 90 95 are preferably made of such length that they pass completely through rod sections 11 and enter apertures 32 in the mandrel 5.

The gut is then in two or more layers which are held along their edges by the rods 12; and when spread out is in condition for 100 stitching by suitable mechanism, such as that described and claimed in copending application Serial No. 446,502, filed February 19, 1921, to form a sausage bag or case formed of a double thickness of gut 105 and of a diameter greater than that of a single section of gut.

If desired, a section of cloth may be used instead of one of the sections of gut for the purpose of increasing the strength and cohesive qualities of the sausage case to be obtained as a final product. Also, instead of a simple section of gut, a previously formed case may be clamped between the rod sections and cut on the mandrel in preparation for stitching. In this manner strips of material may readily be prepared for stitching into bags or cases of very large size. It will be seen that with a mandrel of a size suitable for preparing the original 110 gut, such previously formed cases will not stretch over the mandrel. This is of no importance, however, as it is only in the case of natural sections of gut that the stretching and smoothing effect is necessary.

As a number of modifications may be made in the form and arrangement of the parts illustrated and described without departing from the spirit of the present invention, the scope of the invention is to be 120 125 130

restricted only by the limitations contained in the claims appended hereto.

What I claim is:

1. A device for preparing gut for stitching into bags or cases of increased diameter which comprises a gut receiving mandrel, and a movable mandrel head arranged to secure a section of gut thereon. 5
2. A device for preparing gut for stitching into bags or cases of increased diameter which comprises a gut receiving mandrel, a movable mandrel head, means for extending said head, and resilient means for holding the head in contact with the extremity of the mandrel to secure a section of gut thereon. 10
3. A device for preparing gut for stitching into bags or cases of increased diameter which comprises a tubular gut receiving mandrel, an operating rod passing through said mandrel, a head provided with gut securing means on the forward extremity of said rod, resilient means for normally maintaining said rod in retracted position, and means for extending said rod against the resistance of said resilient means. 15
4. A device for preparing gut for stitching into bags or cases of increased diameter comprising a gut receiving mandrel having a channel therein, gut holding rods arranged to lie in said channel, and a movable mandrel head arranged to secure a section of gut on said mandrel. 20
5. A device for preparing gut for stitching into bags or cases of increased diameter comprising a gut receiving mandrel having a channel therein, gut holding rods arranged to lie in said channel, a movable mandrel head, means for extending said head, and resilient means for holding the head in contact with the extremity of the mandrel to secure a section of gut thereon. 25
6. A device for preparing gut for stitching into bags or cases of increased diameter which comprises a tubular gut receiving mandrel having a channel therein, an operating rod passing through said mandrel, a head provided with gut securing means on the forward extremity of said rod, resilient means for normally maintaining said rod in retracted position, and means for extending said rod against the resistance of said resilient means. 30
7. A device for preparing gut for stitching into bags or cases of increased diameter which comprises a gut receiving mandrel, gut holding rods thereon, means on said mandrel for securing the rearward extremity of said rods in position, and a movable mandrel head arranged to secure a section of gut on said mandrel and to secure the forward extremity of said rods thereon. 35
8. A device for preparing gut for stitching into bags or cases of increased diameter which comprises a gut receiving mandrel, gut holding rods thereon, means on said 40
9. A device for preparing gut for stitching into bags or cases of increased diameter which comprises a tubular gut receiving mandrel, gut holding rods thereon, means on said mandrel for securing the rearward extremity of said rods in position, an operating rod passing through said mandrel, a head provided with gut securing means on the forward extremity of said rod, resilient means for normally maintaining said operating rod in retracted position, means for extending said operating rod against the resistance of said resilient means, and means for securing the forward extremities of said gut holding rods in position. 45
10. A device for preparing gut for stitching into bags or cases of increased diameter which comprises a gut receiving mandrel, jointed gut holding rods having one section thereof extending longitudinally of said mandrel, means for securing said sections on the mandrel, and means for supporting the other sections of said rods. 50
11. A device for preparing gut for stitching into bags or cases of increased diameter which comprises a gut receiving mandrel, jointed gut holding rods having one section thereof extending longitudinally of said mandrel, means on said mandrel for securing the rod sections in position thereon, a movable mandrel head arranged to secure a section of gut on said mandrel, and means for supporting the other sections of said rods. 55
12. A device for preparing gut for stitching into bags or cases of increased diameter which comprises a gut receiving mandrel, jointed gut holding rods having one section thereof extending longitudinally of said mandrel, means on said mandrel for securing the rearward extremities of said sections in position thereon, a movable mandrel head, resilient means for holding said head in contact with the extremity of the mandrel to secure a section of gut thereon, means for securing the forward extremities of said rod sections in position on the mandrel, and means for supporting the other sections of said rods. 60
13. A device for preparing gut for stitching into bags or cases of increased diameter which comprises a tubular gut receiving mandrel, jointed gut holding rods having one section thereof extending longitudinally of said mandrel, means on said mandrel for securing the rearward extremities of said sections in position thereon, an operating rod passing through said mandrel, a head provided with gut securing means on the 65

forward extremity of said operating rod, resilient means for normally maintaining said operating rod in retracted position, means for extending said operating rod against the resistance of said resilient means, means on said head for securing the forward extremities of such sections of the gut holding rods on said mandrel, and means

for supporting the other sections of said rods.

In witness whereof, I hereunto set my hand.

LAURENCE SARTORE.
